UNITED STATES PATENT OFFICE.

GUSTAVE A. WIESER, OF FORT NIAGARA, YOUNGSTOWN, NEW YORK.

DESIGN FOR A PICTURE-FRAME.

SPECIFICATION forming part of Design No. 34,402, dated April 23, 1901.

Application filed April 1, 1901. Serial No. 53,976. Term of patent 3½ years.

To all whom it may concern:

Be it known that I, GUSTAVE A. WIESER, a citizen of the United States, residing at Fort Niagara, Youngstown, in the county of Niagara and State of New York, have invented and produced a new and original Design for Picture-Frames, of which the following is a specification, reference being had to the accompanying drawing, forming part thereof, which illustrates the design.

The leading or material feature of my design consists of a picture-frame having the general form and configuration of an artist's palette. A scroll A is arranged on the upper part of the palette-shaped figure, and in the lower part thereof is a shield-shaped opening B, surrounded by a border C. A panel D is located between the scroll and the shield-shaped opening, and around the opening two

flags E F are draped, with their standards G ²⁰ H crossed. A gun I and a sword J are crossed upon the flags, with their ends only projecting beyond the border C.

Having thus fully described my invention, what I claim, and desire to secure by Letters ²⁵ Patent, is—

The design for a picture-frame as herein described and shown.

In testimony whereof I have signed my name to this specification, in the presence of ³⁰ two subscribing witnesses, at Fort Niagara, Youngstown, New York, this 26th day of March, 1901.

GUSTAVE A. WIESER.
